(57) **CLAIM**

I claim the ornamental design for a video camera, as shown and described.

DESCRIPTION

FIG. 1 is a front-right perspective view of a video camera of the present invention;

FIG. 2 is a front-left perspective view thereof;

FIG. 3 is a rear-left perspective view thereof;

FIG. 4 is a rear-right perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken line showing of the video camera is included for the purpose of illustrating environment and forms no part of the claimed design. Additionally, the dash-dot broken lines define the boundary of the claimed design and form no part thereof.

1 Claim, 10 Drawing Sheets
